CLAIM

The ornamental design for “water conduit retainer”, as shown and described.

DESCRIPTION

FIG. 1 is a perspective view of water conduit retainer showing my new design;

FIG. 2 is a front view thereof;

FIG. 3 is a rear view thereof;

FIG. 4 is a top view thereof;

FIG. 5 is a bottom view thereof; and,

FIG. 6 is an environmental perspective view thereof with the broken line showing of a partial hose being for illustrative purposes only and forming no part of the claimed design.
